United States Patent Office

Des. 189,234

Patented Nov. 15, 1960

189,234

SHOE SOLE OR SIMILAR ARTICLE

Paul A. Crane, 18 William St., Andover, Mass.

Filed Jan. 12, 1960, Ser. No. 59,014

Term of patent 14 years

(Cl. D7—5)

I claim.

The ornamental design for a shoe sole or similar article, as shown.
